UNITED STATES PATENT OFFICE

CLIFFORD A. SCHACHT, OF HUNTINGTON, INDIANA

SLIDING CASTER

Application filed May 25, 1931. Serial No. 539,936.

This invention relates to sliding casters for use on beds, chairs and other articles of furniture or the like, the present application being a continuation-in-part of my copending application Serial No. 536,026, filed May 8, 1931.

The principal object of the invention is to provide resilient sliding casters adapted to be applied to the furniture by merely removing the ordinary casters and replacing same with my casters in the same sockets, said casters being economical to manufacture, having a resilient, semi-resilient, or solid body, with caster pintles mounted therein having a yielding universal rocking movement with respect to the caster body, whereby, when the casters are applied to a chair, the chair can be tilted but the universal movement of the pintles will allow the bases of the casters to remain flat on the surface of the floor at all times, thereby preventing the casters from scarring or injuring the floor or floor coverings.

I will explain the invention with reference to the accompanying drawings which illustrate several practical embodiments thereof to enable others to adopt and use the same; and will summarize in the claims the novel features of construction, and novel combinations of parts, for which protection is desired.

In said drawings:

Fig. 1 is a perspective view of a chair equipped with my novel casters, showing the chair tilted backwardly while the casters on the rear legs remain seated squarely on the floor surface.

Fig. 2 is an enlarged vertical section through one form of caster and pintle.

Fig. 3 is a perspective view of the caster, detached, illustrating the universal rocking movement of the pintle.

Fig. 4 is an enlarged vertical section through a modification of the caster.

Fig. 5 is an enlarged vertical section through a further modified form of caster.

Fig. 6 is an enlarged vertical section through a further modified form of caster.

Fig. 7 is an enlarged vertical section

through a still further modified form of caster.

As shown in Figs. 1, 2 and 3, my novel sliding caster preferably consists of a substantially conical or semi-globular body 1 of resilient molded rubber or other suitable yieldable material, having an axially disposed recess 1a in its upper end of greater diameter than the pintle 2, said recess 1a extending downwardly about one-third the height of the body.

Below recess 1a is a reduced axially disposed bore 1b adapted to snugly receive the lower end of the pintle 2 adjacent its ball-shaped head 2a in order to maintain the pintle 2 normally in vertical position while yieldably permitting universal rocking movement thereof, as illustrated in Fig. 3.

Below the reduced bore 1b is an enlarged cylindrical bore 1c adapted to receive the ball-shaped head 2a of pintle 2, which head 2a has a flattened upper portion 2b adapted to engage the underside of a circular washer 3 snugly fitting the enlarged bore 1c and abutting against the shoulder separating the bores 1b and 1c, said washer preventing the head 2a of the pintle from pulling upwardly through bore 1b. If desired the head 2a of the pintle may have any other desired shape, and the head is not necessarily limited to being ball-shaped. The lower end of bore 1c is cut away as at 1d to accommodate the partially spherical raised socket portion 4a of the cup-like shell 4 which embraces the lower portion of the resilient body 1. The recesses and bores 1a, 1b, 1c and 1d are all preferably molded in the rubber body although same may be cut therein after the body is formed, and the washer 3 and pintle 2 are inserted therein from the underside through recess 1d until the head 2a seats against the washer 3 in recess 1c.

Around the lower portion of the rubber body 1 is a cup-shaped shell 4 of metal, bakelite, glass, wood, or any other material which will slide upon without injuring the floor, said shell 4 being adapted to fit tightly around the lower end of body 1, and being provided at its center with a raised ball-shaped socket seat 4a extending upwardly into the recess 1d.

and bore $1c$, so that the head $2a$ of the pintle will rest in the socket $4a$, whereby the pintle may have a universal rocking movement with respect to the body 1.

5 The resilient body 1 is preferably larger than the inside of the sliding shell 4. While there are a number of ways of inserting the rubber in the shell, I preferably insert the molded body in a partially formed shell 4 (if 10 the shell is made of metal) and then by means of a press contract the upper end of the shell around the body to lock the rubber securely therein.

15 The caster pintle is preferably made with an offset collar or shoulder $2c$ disposed within the recess portion $1a$ of the body 1, said collar or shoulder limiting the downward movement of the plug or plate P mounted on the pintle which carries the furniture leg L , said downward movement under weight of the furniture compressing the flexible upper rim of the resilient body 1 to form a yieldable cushion. The collar or shoulder $2c$ however on the pintle may be omitted if desired, and the shank of the pintle may carry any type of plate or plug.

20 By the above construction the pintle 2 is permitted a universal rocking motion with respect to the body 1 and shell 4, whereby when the chair or other article of furniture is tilted the sliding caster will remain seated squarely on the surface of the floor while the pintle 2 may readily assume the angularity of the furniture leg, thereby preventing injury to the floor.

25 The caster shown in Fig. 4 is substantially the same as that shown in Fig. 2, except that the washer 3 is molded in the rubber body instead of being inserted therein when assembling the pintle; also pintle 2 is somewhat modified the collar ($2c$ of Fig. 2) being omitted and a shoulder $2d$ being formed by reducing the diameter of the upper end of the shank. The body 1 however is otherwise the same as in Fig. 2.

30 In Fig. 5 a modification of the caster shown in Figs. 2 and 4 is illustrated in which the body 1 may be made of molded hard rubber, or may be made of material such as wood, glass, bakelite or the like, and is provided with the bores $1a$, $1b$, $1c$ and $1d$ therein as in Figs. 2 and 4. Around the pintle 2 is placed a tube of yieldable soft material 5, preferably soft rubber, adapted to snugly fit in the upper bore $1a$ to yieldably maintain the pintle 2 in upright position. In place of a tube 5 a soft rubber insert around the pintle 2 may be used, which material is softer or more yieldable than the material of the outer casting or body 1. The soft rubber insert 5 will snugly fit the recess $1a$ and will permit the tilting or rocking motion of the pintle. The harder body 1 can be molded and the soft rubber tube can be inserted therein after molding the body.

In Fig. 6 a further modification is illustrated in which the body 10 is made of solid material such as wood, glass, bakelite, or the like, or possibly hard molded rubber, and the body is provided with an enlarged cylindrical recess $10a$ in its upper end, with a retaining flange $10b$ at its upper end extending into the bore for retaining the soft rubber or other yieldable insert 11 which is inset in the bore $10a$ around the pintle 12. Pintle 12 is provided with a spherical or other shaped head $12a$ adapted to engage a spherical recess $10b$ in the body 10 below the recess $10a$; and a bore $10c$ of greater diameter than the pintle 12 connects the recesses $10a$ and $10b$ whereby the pintle may have a universal rocking movement.

35 The head $12a$ of the pintle seats in a raised ball-shaped seat $14a$ in the shell 14 which is in all respects similar to the shell 4 of Figs. 2, 4 and 5, the seat $14a$ extending upwardly into the bore $10b$ as shown. The soft rubber or other insert 11 extends upwardly around the pintle above the upper end of the body 10 and forms a resilient seat for the plate or plug (not shown) carried by the pintle.

40 In Fig. 7 a further modification of the casters shown in Figs. 2, 4 and 5, is illustrated in which the enlarged bore in the upper end of the resilient body 1 is omitted, and the rubber of the body fits closely against the shank of the pintle 2. The parts are otherwise the same as in Figs. 2, 4 or 5. The type of caster shown in Fig. 7 is adaptable for use on beds, dressers and other articles of furniture which do not require tilting and the rubber body is made to snugly fit the pintle. The washer 3 can be either molded in the recess $1c$ (as in Fig. 4) or placed therein (as in Fig. 2) when assembling the pintle.

45 I do not limit my invention to the exact forms shown in the drawings, for obviously changes may be made therein within the scope of the claims.

50 I claim:—

1. A sliding caster comprising a body having a bore and a recess at the lower end of the bore; a pintle in said bore having an enlarged head disposed within said recess, a washer interposed between the head of the pintle and the upper end of the recess; and a shell mounted around the body having a seat for the head of the pintle.

55 2. A sliding caster comprising a body of molded rubber having a bore with an enlarged recess at its lower end and an enlarged recess at its upper end; a pintle in said bore having an enlarged head disposed within the lower recess; an insert of soft rubber in the upper recess, and a shell of slidale material mounted around the body having a seat for the head of the pintle.

60 3. A sliding caster comprising a body of molded rubber having a bore with an enlarged recess at its lower end and having an

enlarged recess at the upper end of the bore; a pintle in said bore having an enlarged head disposed within said lower recess and adapted for universal rocking movement with respect to the body; a washer molded into the body at the upper end of the lower recess for engagement with the enlarged head; and a shell of slidable material mounted around the body having a seat for the pintle entering the lower end of the lower recess.

10 4. A sliding caster comprising a body of molded rubber having a bore with an enlarged recess at its lower end and having an enlarged recess at the upper end of the bore; a pintle in said bore having an enlarged head disposed within said lower recess and adapted for universal rocking movement with respect to the body; an insert of soft resilient rubber around the pintle and filling the upper recess; and a shell of slidable material mounted around the body having a seat for the pintle entering the lower end of the lower recess.

15 5. A sliding caster comprising a body having a bore with an enlarged recess at its lower end, a pintle in said bore having an enlarged head disposed within the recess; and a shell mounted around the body having a seat for the pintle entering the lower end of the recess, said body being of non-resilient material and having an enlarged recess at the upper end of the bore; and an insert of resilient material around the pintle filling the upper recess.
